UNITED STATES PATENT OFFICE.

RICHARD SAMUEL REYNOLDS, OF BRISTOL, TENNESSEE.

DRINKING-CUP SHIELD.

1,161,730.

Specification of Letters Patent. Patented Nov. 23, 1915.

Application filed November 6, 1914. Serial No. 870,684.

To all whom it may concern:

Be it known that I, RICHARD SAMUEL REYNOLDS, a citizen of the United States, residing at Bristol, in the county of Sullivan and State of Tennessee, have invented 5 certain new and useful Improvements in Drinking-Cup Shields; and I do hereby declare the following to be a full, clear, and exact description of the invention, such as 10 will enable others skilled in the art to which it appertains to make and use the same.

This invention relates to kitchen or table articles, and more especially to cups or glasses; and the object of the same is to 15 produce a sanitary shield which may be slipped over the edge of the drinking cup or glass so that the user's lips will not come in contact therewith.

This object is carried out by constructing 20 the shield in the manner hereinafter described, making it by preference of a rather heavy grade of cardboard, and of such size that it may readily be carried in the pocket or pocket-book.

25 In the accompanying drawings:—Figure 1 is a perspective view of a drinking glass with this shield applied. Fig. 2 is a sectional view of a cup with the shield in section and applied thereto. Fig. 3 is a plan 30 view of a slightly different configuration of the shield itself. Fig. 4 is a plan view showing how a number of these shields of yet different configuration can be cut from a strip of stock with little or no loss of material.

35 In the drawings Fig. 1 shows a glass G and Fig. 2 a cup C which we may assume are drinking utensils such as one finds in public places. We have been taught lately 40 by experts that there is so much infection and contamination conveyed by touching the lips to public drinking receptacles, that in many places the public ice coolers are found without glasses and each person taking 45 a drink is supposed to use his individual cup. While it is undoubtedly true that the majority of people fail to carry with them an individual drinking cup for the sole reason that they have neglected so providing 50 themselves, the fact remains that such cups are bulky to carry in the pocket, will become broken, injured or soiled while in the pocket or from long use, and may at times be mislaid or lost by the most careful 55 person. I have therefore devised a guard which is preferably made from stout card-

board or strawboard stock, oiled or not, and of such size and shape that a number of these devices may be carried in the pocket or pocket-book, or could be stored in an 60 envelop and kept in the desk or any convenient place; and after one has been used for three or four times it can be thrown away.

This article may be employed solely as 65 a precautionary and sanitary expedient for preventing the user's lips from coming in contact with the public drinking glass or cup, or it might be made in numbers, stamped with suitable advertising matter, 70 and given away by department stores and others as a useful novelty.

Referring now to Fig. 3, it will be seen that the contour of this device is, substantially that of a "shield" as commonly employed in heraldry. The upper edge of its upper portion 1 may be and by preference is straight, its body 2 may be about two inches wide and three inches high from said upper edge to its extreme lower end or point, its 80 lower portion 3 is preferably narrower than its body, its upper portion is a little wider than the body so as to produce two ears 4, and the material of which the device is made is cut upward from the angles 5 between 85 the lower ends of the ears and the upright sides of the body, along incisions 6 which may be straight or curved and which preferably converge slightly toward each other as illustrated, thus producing tongues 7 depending from the ears 4 as shown.

In Fig. 4 I have shown how, by alternate guards a number of them could be cut from a strip of cardboard or other stock with little or no waste, the cutting of course being done by dies in a manner not necessary to amplify in this specification. This saving in the stock results from the fact that the upper portion 1 is made of the same length as the lower portion and as much 95 wider than the body 2 as the lower portion 3 is narrower, so that if every other device be inverted its narrow portion will stand between the wide portions of those on 100 both sides of it.

105 In Figs. 1 and 2 the use of this article is shown. The tongues are bent rearward or backward from the user so that the cuts or incisions 6 open slightly, and they are then passed over the upper edge of the tumbler, 110 glass, or other drinking utensil and pressed down sufficiently far to cause the edges of

the incisions to clasp the edge of the utensil, without tearing out the cuts up through the ears to the upper edge. The latter rises above the edge of the utensil as seen, where 5 as the body 2 lies on the outer face of the utensil; and the lower end of the body, or point if it be employed, lies on the outside of the tumbler as best seen in Fig. 1 only the lower ends of the tongues at the extreme 10 side edges of the attachment pass into the glass or cup at all, holding the device in place by their spring action. If they should become wet with the liquid in the act of drinking, no harm is occasioned and nothing 15 is spilled. The user then grasps said utensil with his fingers and thumb, preferably laying the thumb over the body 2 of the shield, and raises it to his mouth, placing his lips over the upper edge and tipping the 20 utensil so that the liquid therein will run out of it and over the upper edge of the shield and into the mouth.

After drinking, the guard or shield may be restored to the user's pocket, especially if 25 it be made of paper which has been oiled so that it may be used several times without injury; or if it be an advertising novelty and of rather thin stock, it will be thrown away after using once or twice.

What is claimed as new is:

The herein described shield for use on drinking utensils, the same made from a single blank of heavy cardboard cut into substantially the shape of a shield and comprising upper and lower portions and a body portion between them, the upper portion being of the same length as the lower portion and as much wider than the body as the lower portion is narrower whereby a number of these devices may be cut from a strip of material with little waste by disposing alternate shields in inverted position, the projecting ends of the upper portion producing ears whose lower edges stand at angles to the sides of the body and the shield being provided with incisions extending from such angles obliquely upward and inward toward each other and producing depending tongues at the sides of the device, for use substantially as herein- 35 40 45 before described.

In testimony whereof I affix my signature in presence of two witnesses.

RICHARD SAMUEL REYNOLDS.
